UNITED STATES PATENT OFFICE.

CLAUDE REES, OF SAN FRANCISCO, AND CHARLES F. HINE, OF OAKLAND, CALIFORNIA.

APPARATUS FOR DRYING SUBSTANCES.

Application filed December 9, 1920. Serial No. 429,298.

To all whom it may concern:

Be it known that we, CLAUDE REES and CHARLES F. HINE, citizens of the United States, and residents, respectively, of the city and county of San Francisco, and of Oakland, county of Alameda, both in the State of California, have invented certain new and useful Apparatus for Drying Substances, of which the following is a specification.

This invention relates to a novel drying system involving the apparatus by which various kinds of substances, and particularly fruits, may be efficiently and rapidly dried to a predetermined degree.

It is very desirable in the drying of certain materials and, particularly, in the drying of fruits as, for instance, prunes, that warm or hot air be passed over and between the substance and yet preserve such a degree of moisture or humidity in the air as will prevent the too rapid drying of the exterior and outermost portion of the fruit.

To that end it is an object of the present invention to provide a system of great capacity and yet of high economy for the drying of fruit in the desired manner and, particularly, it is an object to provide an apparatus in which the substance or fruit being dried may be subjected to circulated air in which the desired degree of moisture or humidity and the desired temperature to secure an economical operation in cost of fuel and to accelerate the process of drying.

It is an object of the invention to provide an apparatus which, while of substantial and simple construction, enables predetermining the course of flow of heated air through the apparatus and it is an object to provide for the control of the circulation of the air and for the substantially constant discharge of a portion of a used, moist air and the admission of fresh air to replace the exhausted air.

It is also an object to provide for the heating of the air before it is discharged into the heating or drying chamber and to provide for the initial heating of the air before it passes to the heating means direct and also to provide means for returning a portion of the used, moist air to the heating means so that it will be reheated, thus providing for the substantially constant circulation and re-circulation of a portion of the air that

has absorbed moisture from the substances being dried, at the same time exhausting a portion of the moist air and supplying fresh air in replacement thereof.

The invention possesses other objects and features of advantage, some of which, with the foregoing, will be made manifest in the following description of the preferred form of the invention which is illustrated in the drawings accompanying and forming part of the specification. It is to be understood that it is not intended to limit the invention to the embodiment shown by the said drawings and description as variations may be adapted within the scope of the invention as set forth in the claims.

Referring to said drawings:

Fig. 1 is a plan view partially in horizontal section of a preferred form of the apparatus.

Fig. 2 is a transverse vertical section through the apparatus substantially on line 2—2 of Fig. 1.

Fig. 3 is a longitudinal vertical sectional view substantially on line 3—3 of Fig. 1.

Fig. 4 is a vertical longitudinal sectional view substantially on line 4—4 of Fig. 1.

Fig. 5 is a horizontal sectional view substantially on line 5—5 of Fig. 2.

In the preferred embodiment of the invention the system comprehends the utilization of a drying house of suitable material and dimensions, the latter being determined by the desired operating capacity. The drying house is preferably of elongated form to facilitate the arrangement therein of a row of tiers, each tier comprising vertically separated or spaced layers of the material to be dried and the layers are preferably arranged in trays of such construction and arrangement that horizontal passageways are formed between the layers to secure the effective traverse of a drying medium such as heated air. To secure efficient, economical and rapid drying of the desired product, the drying house is preferably divided into a longitudinal heat chamber extending along one side of the house and in which chamber there is arranged a series of suitable radiators which are advantageously arranged in a row forming a common plane in which the radiators lie longitudinally; the contiguous vertical sides of the radiators being disposed adjacent a partition or wall

structure forming vertical openings through which air may pass readily from and toward the radiators as determined by the operation of suitable mechanical circulating devices 5 arranged in the drying house.

To secure the desired course of circulation of the heated air through the wall or partition contiguous to the radiators there is arranged, at a suitable height above the 10 floor of the drying house, a horizontal partition or ceiling-like structure beneath which the tiers of layers of substance to be dried can be passed so that the top layers of the tiers are in close proximity to the lower 15 surfaces of the ceiling structure to prevent too free and rapid flow of the heated air immediately beneath the ceiling surface. The drying house is provided with a longitudinal passageway along its opposite 20 side with respect to the heat chamber and which is in free transverse communication with the circulating space formed above the ceiling structure and which space is also in free communication with the upper portion 25 of the heat chamber in which the radiators are arranged so that heated air can be caused to circulate transversely in either direction through the layers of substance to be dried in the tiers in the drying room formed beneath the ceiling structure and between the longitudinal heat chamber and the longitudinal 30 passageway at the opposite side of the house, therefore also permitting the ready circulation of the heated air in either direction 35 through the top spaces above the ceiling by means of suitable mechanical devices which may be controlled so as to reverse the direction of flow of the air at suitable intervals to secure the equable drying effect upon 40 the substance.

An important feature of the present invention resides in the provision for not only circulating heated air to and fro upon the substance to be dried but also in re-using a 45 selected portion of the heated air that has been passed over the substance and that has absorbed moisture therefrom, thus enabling the application of heat to one end of the row of tiers through a medium that possesses 50 such a desirable degree of moisture or humidity as is found extremely practicable and advantageous. Also, an important feature is to provide for the substantially continuous discharge of a selected portion of the 55 air after it has been circulated over the substance and, further, provides also for the admission of a suitable quantity of fresh air in replacement of the exhausted air. Again, it is desirable to economize in the cost of 60 heating the air by utilizing, as above stated, a portion of the previously heated and circulated air and directing this selected portion to means by which it is re-heated. Further, it is desirable to preheat the fresh air passing into the apparatus before it is

discharged directly into the heat chamber and subjected to further heating by radiators in the heat chamber.

It is further a feature of the invention to provide for the variable control of the course 70 of flow of the heated air through the drying house somewhat independently of the mechanical air circulating means and it is also a feature to provide for the ready observation of and access to various tiers of substance 75 while being dried, at the same time without materially disturbing the desired conditions existing in the drying house during the operation of the system.

The system as here disclosed involves a 80 drying house 2 of any suitable material and dimensions and may be of rectangular cross section or otherwise as desired and, for convenient introduction and discharge of the substance to be dried within the drying 85 house, a trackway 3 is extended longitudinally therethrough intermediately between the longitudinal side walls of the house and onto the trackway there may be run suitable trucks 4 on which may be piled tiers 5 of 90 racks or trays 6 to a height such as to enable the tiers to pass beneath an intermediate horizontal ceiling structure 7 above which is formed a circulating air space 8. The ceiling 7 is of less horizontal width than 95 the width of the drying house 2 and there is, therefore, formed along one side edge of the ceiling a free opening 9 while at the opposite edge there is a similar free opening 10 and at suitable longitudinally spaced distances 100 there are transverse vertical partitions 11 for defining spaces above the ceiling 7 in which are arranged suitable mechanical means, as circulating fans 12, secured on shafts 13 that are shown as extending 105 through the side wall 14 and are provided with pulley wheels or other driving means 15 which receive respective pulley belts 16 extended in a series longitudinally of the wall 14. One of the shafts 13 is provided 110 with a tight intermediate pulley 17 flanked by loose pulleys 18 and 19 and from this set of pulleys extends an open and laterally shiftable belt 20 and a cross belt 21 which turn about a driving pulley 22 of the necessary width to accommodate the belts 20 and 21 in their several positions so that the driving pulley may be utilized when operating in one direction through means of the belts 20 and 21 to drive the tight pulley 17 in either direction at intervals during the operation of the drying system and, therefore, securing the rotation of the several fans or propellers 12 on shafts 13 in either direction in their respective sub-spaces above the ceiling 7 and serving to control the direction of circulation of air through the space and sub-spaces above the ceiling for a purpose to be described. When desired, the fan on the shaft 13a may be omitted.

The transverse partitions 11 extend from the ceiling 7 to the side wall 14 and beneath the lower edge of each of the partitions at the opening 10 there is disposed 5 a preferably movable partition or door 23 hinged or otherwise pivotally connected to the wall 14 and having its swinging edge disposed to rest close to an upright or post 24 of which there is a series extending 10 through the drying house in such position as to clear the tiers of material to be dried that are run into the house on the trucks 4. For the purpose of preventing longitudinal leakage of the air in the house past the ends 15 of the tiers, a small vertically hinged shutter 25 may be attached to one side of each of the posts 24; the shutter 25 being hinged so that it is movable toward the contiguous corner of a tier of trays or racks 6, as plainly 20 shown in Fig. 1, to direct the air coming through the opening 10 at the edge of the ceiling 7 laterally toward the tiers. The rate of longitudinal progression of the air may, therefore, be controlled by a suitable 25 angular disposition of the doors 23. This construction, therefore, provides a longitudinal passageway 26 between the wall 14 and the adjacent side of the row of tiers 5 disposed in the drying house through which 30 passageway operatives may have ready passage from one end of the drying house to the other for the convenient inspection of the substance being dried and for the determination of the draft and temperature conditions existing within the house. The tiers 35 5 being coordinate with the transverse partitions 11 from sub-divisions of the longitudinal passageway 26 and prevent the uninterrupted longitudinal flow of air through 40 the house.

To secure the desired and economical heating of the air in the drying house and to secure a substantially constant discharge of a portion of the air and its replacement 45 by fresh air, suitable air heating and supplying means are provided and also suitable means for directing a selected portion of the moisture laden air coming from the substance being dried to suitable portions 50 of the heating means. A preferred form of means for admitting air into the drying house consists of a tunnel-like structure 30 that is preferably constructed of masonry or concrete and which is shown as disposed 55 in the floor of the drying house and spaced inwardly from the longitudinal side wall 31 thereof. The tunnel is shown as being sunken somewhat below the floor and extending upwardly a suitable distance therefrom, one longitudinal side of the tunnel 30 paralleling the trackway 3. At the opposite sides of the trackway there are provided a series of adjustable closures or shutters 32 that may be pivoted at their lower 60 edges 33 so that their upper edges can be

swung toward the bottom trays of the tiers and, therefore, preventing the passage of air transversely beneath the bottom of the tiers.

The house 2 may be of any length, as 70 stated, and as shown has capacity for containing six trucks of tiers which extend substantially from end to end of the house, one end being provided with an ingress door structure 34 while the opposite end is 75 provided with an exit door structure 35. The air tunnel 30 extends along the floor of the drying house from a position at one end adjacent the outlet door 35 forwardly to a suitable point at which there may be 80 provided an L-shaft or branch 30' extending horizontally and provided with an intake mouth 30^a through which fresh air may pass into the branch 30' and the tunnel 30 proper. The tunnel 30 is shown as about 85 equal in length to the length of a series of four tiers of the trays on trucks 4 and arranged upon the top of the tunnel in a longitudinal row thereon and in spaced relation to register medially with the tiers 90 5 are suitable types of radiator structures comprising each, for instance, a bottom manifold 37 and a top manifold or header 38 between which extend vertical rows of heat flues or tubes 39 through which heated air may be circulated in a predetermined 95 course.

The tubes of the radiator stand in suitable spaced relation from the wall 31 in rows that are parallel to the wall and to the adjacent sides of the tiers of trays so that there is formed along the inside surface of the wall 31 a heat chamber 40. For the effectual control of the flow of air to and from the chamber 40 past the radiating 100 tubes 39 of the radiators and toward and from the horizontal spaces between the layers of material in the trays in the tiers 5 suitable deflecting walls of partitions 41 are arranged vertically and with their planes oblique to the length of the central drying room in which the tiers are arranged; contiguous partitions 41 converging inwardly and meeting at 42 so that heated air passing from the heat chamber 105 40 through the radiators may freely spread when passing the diagonal partitions 41 and, conversely, the heated air passing from the tiers toward the radiators is converged 110 in streams directed intimately against the radiator tubes. To prevent free longitudinal movement of heated air along the longitudinal heat chamber 40 during the operation of the apparatus, suitable transversely extending doors 43 are provided and extend from the side wall 31 to a stationary support and panel part 44 adjacent the angle 42 of the oblique deflectors 41, these doors 43 permitting passage of operatives readily along the heat chamber 40 as occasion may require. 115 120 125 130

To secure the maximum efficiency of heating apparatus for the economical heating of fresh and re-circulated air in the apparatus adjacent pairs of the radiators, including 5 the lower manifolds 37, the upper manifolds 38 and the connecting tubes 39, are served by common furnaces 45 of any suitable type which are shown as extending laterally from drying house 2 through the side wall 10 31, each furnace discharging its hot gases and products of combustion into the respective horizontal drum 46—47, Fig. 4, which drums are disposed in the tunnel 30. The drum 46 serves the pair of radiators adjacent 15 the discharge end and is connected to these radiators through upwardly extending tubes 48 leading into the bottom of the adjacent bottom manifold, as 37, from which the heated gases pass into the 20 connecting tubes 39 while the longitudinally extending heat drum 47 is similarly connected to the forward pair of radiators through connecting tubes 49 leading into the bottom manifolds 37 of the respective radiators. The several connecting tubes 48—49 25 may be and preferably are provided with regulating dampers 50. Fresh air passing into the mouth 30^a of the tunnel 30 flows longitudinally through the tunnel 30 which 30 is provided at a suitable location adjacent its rear end with a small discharge aperture 51 in the side of the tunnel adjacent the wall 31, and further beyond is provided with a larger discharge opening 52 through 35 which the fresh air which is heated by contact with the drums 46—47 discharges into the heat chamber 40 along the side of the house. The fresh air may then rise at the rear end of the heat chamber to freely mix with the 40 air circulating therein and through the apparatus.

It is an important function of the present system to re-circulate a portion of the air through the entire house so as to maintain 45 a predetermined degree of moisture or humidity in the air as has been found desirable to prevent too rapid and undue drying of the material adjacent the discharge end of the drying room and also to prevent 50 the hardening of the exterior portion of the substance as it is initially introduced into the drying chamber. To that end, means are provided for subtracting a portion of the air from the intake end 55 of the drying room and discharging the same to the atmosphere exterior to the house, a certain portion of the moist air being by said means restored to the space within the house to be re-used and re-circulated 60 and, also, to be reheated.

A means for accomplishing this function is illustrated as comprising a suction blower 55 including a fan or wheel arranged in a housing 56 disposed in a vertical position with an opening in one end wall so

that air can be drawn inwardly at its side remote from the adjacent tier 5. To form the extension of the heat chamber 40 and separate the same from the drying room in which the tiers are arranged, a partition 70 54 extends from the first radiator toward the end 34 and the blower casing 56 is mounted in the partition, the front end of which partition may be provided with a passageway 54' to permit a portion of the 75 air from the drying room to pass around the end of the partition 54 toward the outer side of the partition 54, such air being drawn into the blower 55 when it is operated. The blower casing 56 is provided with 80 a lower tangential discharge branch 57 which is divided and forms an exhaust or discharge flue 58 leading substantially vertically upward and discharging to the atmosphere through the house structure 2, while the discharge branch 57 is also provided with an extended connection or flue 59 that may project obliquely upward 85 toward the roof of the house 2 and thence extend in the form of a horizontal conduit 90 60. This conduit terminates at a location between the intermediate radiators and extends downwardly in a leg 61 which opens into the tunnel 30 at a location between the contiguous ends of the drums 46 and 47. 95

For the purpose of selecting a portion of the heated and moist air coming from the drying room and drawn into the blower casing 56 so that the selected portion can be re-used and also for determining the 100 quantity to be discharged or exhausted through the outlet flue 58, the end of the discharge pipe 57 of the blower is provided with a suitable regulator or valve 62 at the intersection of the outlet flue 58 and the flue 59, which latter leads the selected portion of moist air through the conduit 60 and the leg 61 into the fresh air tunnel 30 where it is passed about the farther heat drum 46 where it is re-heated and thence passes through the openings 51 and 52 of the tunnel wall into the heat chamber 40. The volume of flow in the flue 58 is controlled by a damper 58' and by valve 62. From this, it will be seen that instead of 110 fresh dry air only being taken as a new supply through the warming tunnel, there is added to the fresh air taken in through the mouth 30^a of the tunnel a predetermined proportion of previously used moist air, thus not only conserving the heat produced by the furnaces and transmitted by the radiators to the circulated air, but also obtaining and maintaining the desired degree 115 of humidity and also securing fresh air in replacement of the exhausted air passing through the outlet flue 58.

It will be seen that the fresh air passing into the mouth of the tunnel will be pre- or initially heated by its contact with the heat 120 125

drums 46 and 47, which are disposed in the tunnel, before it is discharged from the tunnel into the heat chamber 40 to be further heated by passing it to and fro about the 5 radiator tubes 39. Again, as above stated, that portion of the heated moist air drawn from the drying room by the blower 55, and which is passed through the return conduit 59, 60, 61, is also reheated while still in its 10 moist condition.

Power to drive the various circulating fans and blower may be derived from any suitable source, not shown, and transmitted to the shaft of the blower 55 from the 15 overhead transverse main shaft 13^a on which is provided the master pulley 22. This transmits power, through the pulleys 20—21, to the loose and tight pulleys 17, 18 and 19 by which the direction of drive of the several 20 fan shafts 13 is determined by the attendant to secure the rotation in alternate directions of the fans 12 at predetermined and desired intervals and for suitable periods.

The general course of the current of air 25 passing through the apparatus is characteristically helical, this being secured by reason of the provision of the transverse panels and partition forming means which divide the longitudinal drying room into a series of 30 sub-chambers on each side of the several overhead partitions 11 with which are co-ordinating side doors 23 and 43; there being in each of the sub-chambers or spaces a circulating fan or propeller 12. In the rotation of the fans in one direction air is drawn 35 upwardly from the heat chamber and thence transversely across through the spaces 8 above the ceiling 7 and driven down between the adjustable doors or partitions 23 40 which serve to direct the current of air inwardly toward the drying room where the air passes substantially horizontally through the spaces formed between superposed layers 45 of the material to be dried and which is contained in trays or racks and from which the air passes toward the radiator tubes 39 by which it is heated. By angularly adjusting the several doors or partitions 23 more or less of the air tends to move longitudinally 50 toward the inlet end of the drying house diverted from one of the transverse spaces 8 toward the next through which it is driven across the drying room beneath the ceiling 7 to the opposite side where it is again re-heated by the radiator. This gradual advancement of the warm air continues until 55 it passes about the first tier of trays and is drawn by the blower into the discharge and returning flues. The free, longitudinal progression of the current of air is prevented by the shutters 25 which serve to deflect the air transversely toward the contiguous tier of trays. When the shutters are set against the sides of the tiers, a small portion of the 60 air may creep or escape through the spaces 65

formed between the edges of the shutters and the adjacent tiers. It is found in practice that in a given installation or system sufficient heat can be secured from a row of four radiators disposed in proximity to a row of 71 four tiers in advance of which there may be a plurality of tiers adjacent which no radiators are provided.

What is claimed is:

1. An apparatus for drying substance, 75 comprising a drying room in which the substance may be arranged, means for circulating air through the room, means for discharging a portion of the circulated air, means for replacing the discharged air by 80 fresh air and including a fresh air conduit, heating drums in the conduit, and means for heating the air before it reaches the substance and after leaving the conduit.

2. An apparatus for drying substance, 85 comprising a drying chamber in which the substance may be arranged, a plurality of compartments opening into said chamber, air heating means in said compartments, a conduit through which fresh air is conveyed to 90 the compartments, heating means in said conduit and means for circulating the heated air through the chamber and compartments and for returning a portion of it to the compartments through said conduit. 95

3. An apparatus for drying substance, comprising a drying room in which the substance may be arranged, heating means including pre-heating gas drums and flues 100 and secondary elements, means for conveying fresh air to the heating means so that the air may be heated in stages by said drums and flues, and means for circulating the heated air through the room and returning a part of it to the heating means by way of the fresh air conveying means. 105

4. An apparatus for drying substance, comprising a drying room in which the substance may be arranged, heating means including horizontal drums, means for conveying fresh air to the heating drums so that the air may be heated, and means having branches for circulating the heated air through the room and returning a part of it to the heating means, the air being acted upon at a plurality of stages by the heating means. 110

5. An apparatus for drying substance, comprising a drying room in which the substance may be arranged, heating means arranged along one side of the room, a conduit enclosing a part of the heating means and for conveying fresh air to the heating means so that the air may be heated, and means for circulating the heated air through the room and returning a part of it to the conduit, the air being initially heated in the conveying means, and reheated after discharge therefrom. 115

6. An apparatus for drying substance,

comprising a drying room, in which the substance may be arranged, heating means, means including a conduit independent of the room structure for conveying fresh air to the heating means, and means for circulating the heated air through the room and valved flues for returning a part of it to the conduit, and discharging a part of it.

7. An apparatus for drying substance, comprising a drying room, in which the substance may be arranged, heating means, a conduit for conveying fresh air to the heating means, and means including valved flues for circulating the heated air through the room and returning a part of it to the heating means by way of the fresh air conveying conduit so that a mixture of fresh heated air and of moist re-heated air is passed over the substance.
8. An apparatus for drying substance, comprising a drying chamber, a radiator arranged adjacent one side of said chamber, a fan for circulating air through said radiator and chamber, a furnace, a conduit for the gases of combustion connecting said furnace and radiator, and walls forming a chamber in which the conduit is disposed, said latter chamber being provided with ports opening to the atmosphere and to said drying chamber.

9. An apparatus for drying substance, comprising a chamber divided into two compartments by a horizontal wall, said compartments being connected together at their ends, a fan arranged in the upper compartment to circulate air through the chamber, a radiator arranged in the lower compartment through which the air passes, a conduit for gases of combustion arranged below and connected to the radiator, and walls forming a chamber in which the conduit is disposed, said latter chamber being provided with ports opening to the atmosphere and to said first chamber.

10. An apparatus for drying substance, comprising a drying chamber; tiers of trays in said chamber for the substance to be dried

arranged with a passage above the material on each tray extending through the tiers transversely only of said chamber, fans for blowing a mass of heated air transversely across said chamber and through said passages, a blower arranged at the end of the chamber for causing a gradual progression of said mass of air longitudinally through said chamber and means for varying the amount of air entering said blower.

11. An apparatus for drying substance, comprising a drying chamber, tiers of trays in said chamber for the substance to be dried arranged with a passage above the material on each tray extending through the tiers transversely only of said chamber, fans for blowing a mass of heated air transversely across said chamber and through said passages, a blower arranged at the end of the chamber for causing a gradual progression of said mass of air longitudinally through said chamber and conduits connected to the blower for discharging a portion of said air into the atmosphere and the residue into the opposite end of the chamber.

12. An apparatus for drying substance, comprising a drying chamber, tiers of trays in said chamber for the substance to be dried arranged with a passage above the material on each tray extending through the tiers transversely only of said chamber, fans for blowing a mass of heated air transversely across said chamber and through said passages, a blower arranged at the end of the chamber for causing a gradual progression of said mass of air longitudinally through said chamber and conduits connected to the blower for discharging a portion of said air into the atmosphere and the residue into the opposite end of the chamber, and means for heating said returned air before it enters said chamber.

In testimony whereof, we have hereunto set our hands.

CLAUDE REES.
CHARLES F. HINE.
